JOHN E. HOY, OF MIDLAND, MICHIGAN, ASSIGNOR TO THE DOW CHEMICAL COMPANY,
OF MIDLAND, MICHIGAN, A CORPORATION OF MICHIGAN

COMPOSITE CASTING

Application filed March 29, 1924. Serial No. 702,996

In order to overcome the undue expansion of internal combustion engine pistons formed of light metal alloys, as well as for the sake of the better bearing contact that is obtained between the cast iron cylinder bore and a piston having a skirt likewise of cast iron or of steel, a variety of pistons have been proposed having a composite structure. That is, the bodies of such pistons have been made of a light metal alloy, for example, one of the numerous magnesium base alloys available for the purpose, and the skirt of the piston has been surrounded by, or encased in, a shell of cast iron or steel, or one or more iron bands, as distinguished from the loosely fitting piston ring, have been attached to the piston skirt. A serious difficulty, however, is encountered whenever it is thus attempted to firmly attach to a light metal piston, with its relatively high coefficient of expansion, a band of metal having a lower coefficient of expansion. In other words, when such a composite piston is subjected to the changes of temperature encountered in the operation of an internal combustion motor the band will either work loose or the piston skirt be so distorted as to detract seriously from the utility of the device.

The object of the present invention is the production of a light metal alloy piston, primarily one designed for use in internal combustion engines, to which piston is permanently attached one or more bands of cast iron or steel in such a manner as always to remain firmly in contact with the piston body proper, irrespective of changes in temperature. At the same time any tendency towards distortion of the body of the piston is avoided.

To the accomplishment of the foregoing and related ends, the invention then consists of the means hereinafter fully described and particularly pointed out in the claims, the annexed drawing and the following description setting forth in detail certain mechanism embodying the invention, such disclosed means constituting, however, but one of various mechanical forms in which the principle of the invention may be used.

In said annexed drawing:—
Fig. 1 is a side elevation of a piston em-

bodying my present improvements; Fig. 2 is a central vertical section thereof, the plane of the section being indicated by the line 2—2, Fig. 1; Fig. 3 is a horizontal transverse section of the piston, the plane of the section being indicated by the line 3—3, Fig. 2; Fig. 4 is a vertical section of a detail, the plane of such section being indicated by the line 4—4, Fig. 3; and Fig. 5 is a perspective view of the shell of cast iron or steel that forms one of the composite parts of such piston, such shell being shown separate from the piston.

In its general features of construction, my present improved piston is similar to those of cast iron or light metal alloys heretofore used in internal combustion engines. In other words, such piston comprises a more or less cylindrical head portion 1, from which depends a sleeve or skirt portion 2. The latter is formed with oppositely placed inwardly directed bosses 3, which are apertured to receive the wrist pin (not shown), whereby the piston is attached to the connecting rod. Bushings 4 of bronze or equivalent bearing metal are preferably fitted to the apertures in such bosses and an integral rib 5 between each boss and the head 1 contributes to the strength of the structure. In order effectually to seal the piston within the walls of the cylinder in which it works, resilient piston rings (not shown), of familiar construction, are seated in annular recesses 6 in the head portion 1, as need not be here explained.

The present improvement in the specific form illustrated consists in the application to the skirt portion 2 of a shell or band 7 that entirely surrounds the same adjacent its lower edge, such shell being formed on opposite sides with vertically extending portions 8 that rise approximately to the height of the wrist pin axis but are located half way between the respective ends of such wrist pin, or in other words between the openings in bosses 3. The exterior surface of such shell 7, including the portions 8 thereof just referred to, is strictly cylindrical to conform with the cylindrical surface of the piston skirt 2 and of the same diameter as the latter. It will be understood, in other words, that

the metal composing the piston proper (head 1 and skirt 2) is cast in a suitable mold in which such shell has been previously placed, the walls of the mold being formed to give the proper contour to the exposed portions of the body and skirt. The exterior surface of the latter, including the lower edge 9 thereof, which projects below the lower edge of the shell, will accordingly lie flush 10 with the exterior surface of the shell.

As best shown in Figs. 3 and 4, the shell is provided with a plurality of inwardly projecting studs 10. These are of general conical form, their free or inner ends being 15 larger than their outer ends which merge in the material of the shell and they are preferably formed integral with the latter. Such shell, as shown in the same figures, is further provided with a plurality of openings 11 20 which are likewise of general conical form, the outer ends of the openings being of larger diameter than their inner ends, i. e. the walls of such openings converge to points within the piston. The studs 10 are of such length 25 as to extend through the metal of the skirt when the latter is cast within the shell, so that the heads of such studs lie substantially flush with the inner surface of the skirt. The metal of the latter in casting will also flow 30 into and fill the openings 11 in the shell, so that the skirt is in effect provided with a complementary series of studs 12 (see Figs. 2 and 4) that have their larger ends directed 35 outwardly and lying substantially flush with the outer surface of the shell.

The several studs 10 and 12, wherewith the piston skirt and the shell that surrounds the same are thus provided, will preferably be spaced in staggered relation circumferentially 40 about the parts in question and also vertically where, as in the preferred construction shown, the shell comprises the two opposite upstanding portions 8.

The studs or lugs 10 on the shell not only 45 serve to center the latter around the core in the operation of casting the piston, but also clench the skirt to such shell when the piston is poured. A similar clenching effect is likewise obtained by the reversely directed studs 50 or lugs 12 that are formed by the metal of the skirt which fills the countersunk openings 11 in the shell. As a result of the foregoing construction, any tendency on the part of the shell to become loose on the piston skirt, incidentally to changes of temperature, due to 55 the different coefficients of expansion of the metals composing the parts in question, is counteracted inasmuch as the flaring studs 10 on the shell and the oppositely flaring studs 60 12 on the skirt will seat more tightly, whether the skirt contracts more rapidly than the shell or the shell expands more rapidly than the skirt. The effect, of course, of expansion of 65 the skirt at a rate in excess of that of the shell merely presses the former that much more

forcibly against the latter. Furthermore, the projections of the metal of the skirt in the form of studs 12 through openings 11 in the shell affords a direct path for the conduction of heat from the body of the piston to the cylinder wall, to this extent obviating the objection to composite pistons of the type in hand, viz., that the escape of heat from the piston is interfered with because of the lower thermal conductivity of the shell.

It will be understood, of course, that the body of the piston may be either cast or forged and that the particular manner of fabrication of the surrounding shell, whether, in other words, it be a casting, stamping, or forging, does not affect the principle involved in my invention. It has already been explained that the shell need not be of the particular form shown by way of illustration in the drawing, but that it may consist of a simple band without, in other words, the upstanding portions 8; also that a plurality of vertically spaced bands, instead of a single band or shell, may be utilized, if found desirable. While I have hereinbefore spoken of the light metal alloy, whereof the piston body proper is composed, as being a magnesium base alloy, i. e. one in which magnesium is the predominant constituent, it will be understood that pistons made of any equivalent alloy, such as the well known aluminum base alloys, may be advantageously fitted with a shell of another metal or alloy in the manner hereinbefore described and better bearing qualities thus secured for such piston while 100 at the same time avoiding the difficulties that have heretofore inhered in pistons of composite construction.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a piston, or like article, the combination with a head and integral skirt depending therefrom; of a cylindrical shell closely surrounding said skirt and composed of a material having a different co-efficient of expansion, said skirt and surrounding shell each having a plurality of projections extending through to the respective surfaces and formed to have clinching engagement and an even surface level.

2. In a piston or like article, the combination with a head and integral skirt depending therefrom; of a cylindrical shell closely surrounding said skirt and composed of a material having a different co-efficient of expansion, said skirt and surrounding shell each having a plurality of projections extending through to the respective surfaces

and being of general conical form with their free ends the larger whereby said head and shell are clinched together.

3. In a piston, the combination with a body comprising a head and an integral skirt depending therefrom, said body being composed of a light metal alloy; and a cylindrical shell of ferrous metal surrounding said skirt, the latter and said shell each having a plurality of projections extending through to the respective surfaces and formed to have clinching engagement and an even surface level.

10 4. In a piston, the combination with a body comprising a head and an integral skirt depending therefrom, said body being composed of a light metal alloy; and a cylindrical shell of ferrous metal surrounding said skirt, the latter and said shell each having a plurality of projections extending through to the respective surfaces and being of a general conical form with their free ends the larger whereby said body and part are clinched together.

15 5. In a piston, the combination with a body comprising a head and an integral skirt depending therefrom, said body being composed of a light metal alloy; and a cylindrical shell of ferrous metal surrounding said skirt, said shell being formed with holes 20 wherein the material of said skirt extends, and such holes and the corresponding lugs on said skirt being of general conical form with walls converging to points within the piston.

30 35 Signed by me this 26th day of March, 1924.

JOHN E. HOY.
